UNITED STATES PATENT OFFICE.

EDWIN W. PIERSON, OF NEWARK, NEW JERSEY, ASSIGNOR TO INTERTYPE CORPORATION, OF BROOKLYN, NEW YORK, A CORPORATION OF NEW YORK.

AUTOMATIC CUT-OUT FOR TYPOGRAPHICAL MACHINES.

1,406,075.

Specification of Letters Patent.

Patented Feb. 7, 1922.

Application filed May 27, 1921. Serial No. 473,008.

To all whom it may concern:

Be it known that I, EDWIN W. PIERSON, a citizen of the United States, residing at Newark, in the county of Essex and State of New Jersey, have invented new and useful Improvements in Automatic Cut-Outs for Typographical Machines, of which the following is a specification.

The present invention relates to improvements in typographical machines of the linotype class wherein the operations of conveying an assembled line of matrices to a mold and the casting of a type bar or slug therefrom are performed periodically, or following the composition of each line by the operator, the continued operation of the machine, after each casting operation distributing and returning the matrices used in each line, to the magazine.

Machines of this class are commonly driven by electric motors, each machine being provided with a motor which is individual thereto and runs continuously while the machine is in use, and a manual switch is provided by which the operator may start and stop the motor, when the use of the machine is commenced or terminated. Practice has shown, however, that the usual manual switch for starting and stopping the motor does not secure the desired economy in the consumption of electric current, nor does it avoid unnecessary wear on the machine, in the routine of work in a composing office where the operators frequently leave their machines for longer or shorter periods of time and neglect to operate the usual manual switch to cut off current to the motor and the lights on the machine. The expense incurred on this account, especially where as is usual, a large number of machines is employed, is a substantial loss.

The object of the present invention is to provide means for automatically cutting off current to the motor and also, if desired, to the lights used in the machine, in the event that the operator leaves the machine for a period of time longer than that required for the distribution of the matrices used in the line from which the last cast was made, thus obviating the objections which practice has shown to exist where the ordinary manual switch is employed to start and stop the motor. The automatic current cut-off provided by the present invention does not interfere, however, with the continuous oper-

ation of the motor while the machine is operating regularly in performing its usual functions of delivering the lines of matrices to the mold and the casting of type bars or slugs therefrom, although it will operate with certainty to cut off the supply of current after a suitable period of idleness has elapsed following the casting of the last type bar or slug.

To these and other ends, the invention consists in certain improvements and combinations and arrangements of parts, all as will be hereinafter more fully described, the features of novelty being pointed out particularly in the claims at the end of the specification.

In the accompanying drawing:—

Figure 1 is a side elevation, partly in section, of an automatic cut-out constructed in accordance with the present invention and applied to a line casting machine of the linotype class;

Figure 2 is a front elevation of the device, partly in section, showing the controlling connection between the cut-out and metal pot of the machine; and

Figure 3 is a detail perspective view of the switch which controls the supply of electric current to the machine.

Similar parts are designated by the same reference characters in the several views.

The present invention is applicable generally to electric-motor-driven typographical machines of the linotype class, as shown and described generally in the patent granted to Ottmar Mergenthaler, No. 436,532, dated Sept. 16, 1890, and to any other electric-motor-driven typographical machine employing a similar cycle of operations. The preferred embodiment of the invention is shown in the accompanying drawing and will be hereinafter described in detail, but it is to be understood that the invention is not restricted to the precise construction shown and described, as equivalent constructions are contemplated and these will be included within the scope of the claims.

In the present instance, the cut-out mechanism is supported and substantially enclosed within a housing 1 which may be suitably mounted or supported on the framework of the machine. In the present instance, the housing is supported at its lower end by the part of the frame designated 2, by a screw 3 which extends through said part

of the frame and is threaded into a lug 4 which projects from the bottom of the housing, and a set screw 5 threaded in the lug 4 bears against the part of the frame 2 and 5 serves as an adjustment to position the housing and the cut-out mechanism enclosed therein, with respect to the part of the operating part of the machine from which the cut-out mechanism is driven. The upper 10 portion of the housing may be supported or braced by a bar 6 which is secured to the housing by the screw 7 and this bar may be attached to an adjacent part of the stationary frame of the machine.

15 The cut-out mechanism comprises a screw 8 which is journalled at its ends in the front and rear walls of the housing and a slide or carriage 9 which is mounted to travel in parallelism with the axis of the screw and 20 carries a blade or tooth 10 which is shaped and arranged to engage the threaded portion of the screw, so that while this tooth is engaged with the revolving screw, the carriage will be shifted in a direction from the full 25 line position, toward the dotted line position, as shown in Figure 1. The carriage is also movable in a direction transversely of the screw to cause engagement or disengagement of the tooth or blade 10 relatively to the screw. Preferably and as shown, the carriage is mounted to slide longitudinally on a 30 squared, or other suitably shaped rock shaft 11, the ends of which are rotatably journalled or supported by the housing. A tension spring 12 attached at one end of an arm 13 which projects laterally from the rock shaft 11 and fixed at its other end to a hook or eye 14 on the casing, acts with a tendency to swing the carriage 9 toward the screw and 35 40 to engage the tooth or blade 10 thereon with the threaded portion of the screw, so that the revolving motion of the screw will act to advance the carriage in the direction above described. A tension spring 15 attached at one end to the stud or projection 16 on the carriage and at its opposite end to the stud or projection 17 on the rock shaft 11, acts with a tendency to yieldingly hold the carriage in the full line position shown in 45 50 Figure 2, and to restore the carriage to the said full line position, after it has been advanced to or toward the dotted line position (Figure 1) and then displaced to disengage the tooth or blade 10 thereon from the screw.

55 The carriage controls the supply of electric current to the electric driving motor of the machine and preferably also to the lights, when such are used in the machine. In the present instance, a switch is employed, the 60 terminals 18 and 19 of which are adapted to be bridged by a switch plate or member 20, to complete the electric circuit through which the electric current is supplied to the electric driving motor and the lights. The 65 terminals 18 and 19 are preferably fixed to an insulating base 21 which is suitably secured in stationary position within the housing by the screws 22. The switch plate or member 20 may, as shown, consist of a strip of flexible metal, one end of which is fixed 70 by the screw 23 to one of the terminals, the terminal 19 in the present instance, while its opposite end 24 has a normal tendency to engage the terminal 18, but may be moved or pressed out of engagement therewith, by 75 the carriage 9 when the latter has been advanced to a sufficient extent by the screw 8. The control of the switch member 20 by the carriage 9 is effected, in the present instance, by the projection 25 which may be composed 80 of fiber or other suitable insulating material secured to the carriage 9, this projection being so arranged that it is located in line with the switch member 20 when the carriage occupies a position with its tooth or blade 10 85 in operative engagement with the screw, but said projection will be out of line with the switch member 20 when the carriage is swung into a position to disengage the tooth or blade 10 thereon relatively to the screw. It 90 will be understood that electric switches of different kinds may be used to control the supply of electric current to the machine, the switch shown and described being but one form of switch suitable for the purpose. In 95 this arrangement, when the carriage 9 occupies the full line position shown in Figure 2, the switch-operating projection 25 thereon will be retracted, relatively to the switch member 20, and the latter will then complete 100 the circuit between the terminals 18 and 19; and when the carriage 9 has been advanced by the screw 8 to substantially the position shown by the dotted lines in Figure 1, the switch-operating projection 25 will have 105 reached a position where the movable end 24 of the switch member is disengaged from the terminal 18 and the circuit through which electric current is supplied to the machine will then be interrupted. If the carriage 9 110 is swung laterally in a direction away from the screw 8 while the carriage occupies the dotted line position represented in Figure 1, the projection 25 on the carriage will be withdrawn laterally from engagement with the switch member 20, thus permitting the latter to snap into engagement with the terminal 18 and thereby reestablish the electric circuit through the machine and by this same 115 operation, the tooth or blade 10 on the carriage will be disengaged from the thread of the screw and the spring 15 will act automatically to restore the carriage to the full lines position shown in Figure 1. A handle or lever 26 is preferably fixed to the forward 120 end of the rock shaft 11 to provide means for manually rocking the shaft 11 to trip the switch and to restore the carriage to its retracted or initial position, thus enabling the operator to start the machine into operation 125 130

after its operation has been interrupted by the cut-out. According to the present invention, the cut-out will automatically interrupt the operation of the machine when the 5 latter ceases to perform its periodic cycles with the usual regularity, or in other words, where an abnormal period of time elapses after the completion of one cycle of operations and the repetition of such cycle of operations. This result is attained by causing the 10 screw 8 to revolve in unison with a suitable continuously-running part of the machine and tripping or releasing the carriage 9 periodically by a suitable part of the machine 15 which participates in the periodic cycle performed by the machine. In the present instance, the screw 8 is driven preferably by the intermediate shaft 27 which, in machines of the linotype class, revolves continuously 20 while the electric-driving motor is running and it serves to drive the continuously-running distributor. For the purposes of the present invention, this shaft may have a screw or worm 28 fixed thereon, this screw 25 or worm having a single thread 29 and the screw or worm engages a tooth or worm wheel 30 which is fixed to the screw 8, the latter being thereby driven in a direction to cause the carriage 9 to advance from the initial or full line position to or toward the 30 dotted line position shown in Figure 1, while the tooth or blade 10 on the carriage engages the thread of the screw 8.

Tripping or releasing of the carriage to cause its return to initial position is preferably controlled by the advance of the metal pot toward the mold, preparatory to the performance of a casting operation. As shown, the metal pot 31, which corresponds to the 40 metal pot usually employed in typographical machines of the linotype class and which approaches and recedes relatively to the mold, incidental to each casting operation, is provided with a cam or wedge 32 at one side 45 and a roller 33 carried by a reciprocatory bar 34 rides on the cam or wedge 32; the advance of the metal pot toward the mold causing the bar 34 to shift toward the right, as shown in Figure 2, while the receding 50 movement of the metal pot permits the bar 34 to return toward the left. The bar 34 is suitably guided by the frame of the machine and it is pivotally connected at one end to the lower end of a lever 35, the latter being 55 pivoted at 36 to the part of the frame 2 and the upper end of this lever is provided with a finger 37 which is arranged at one side of an arm or projection 38 which is fixed to the rock shaft 11, the finger 37 being caused to 60 engage the arm 38 and to rock the shaft 11 into the position shown in Figure 2, thus tripping the carriage 9 by disengaging its tooth or blade 10 from the thread of the screw 8, when the metal pot advances relatively to the mold, preparatory to a casting 65

operation, the finger 37, however, being clear of the arm 38 after the metal pot has receded from the mold and the spring 12 has restored the lever 35 and the bar 34 to their initial position. 70

The mode of operation of the cut-out herein shown and described, is briefly as follows:—

To start the machine in operation, the handle or lever 26 is manipulated to swing the carriage 9 laterally into the position shown in Figure 2, this operation disengaging the tooth or blade 10 on the carriage from the thread of the screw 8 and causing the restoring spring 15 to return the carriage to the initial position shown by the full lines in Figure 1. By this operation, the switch member 20 is caused to bridge the terminals 18 and 19, thus completing the circuit through which electric current is supplied to the electric driving motor of the machine and also the lights, when such are used. The continuously-running parts of the machine, including the intermediate distributor-driving shaft 27, are then set into 80 operation and owing to the connection between the continuously-revolving shaft 27 and the screw 8, the latter is revolved continuously. The tooth or blade 10 on the carriage which is normally held in operative 85 engagement with the thread of the screw 8, by the spring 12, then causes the carriage 9 to advance from the full line position toward the dotted line position (Figure 1).

During the first part of the advancing movement of the carriage 9, the operator is assembling the matrices to form a line, or if a line has already been assembled, such line is caused to advance to the casting mechanism, this being the first part of a period-

ically or intermittently performed cycle which is initiated by the operator who releases a clutch and sets into operation mechanisms for justifying the line, for positioning the mold to cast a type bar or slug, to ad-

vance the metal pot up to the mold, to operate the pump to inject metal from the metal pot into the mold and to restore these elements to their normal positions, after

which the line of matrices from which the cast was made is distributed and the matrices are returned to their appropriate channels in the magazine by the continuously-running distributor. While a typographical machine of this class is in use, this cycle of

operation is repeated with more or less regularity and while the carriage 9 will have been advanced by the screw 8 to bring the switch-controlling projection 25 thereon

nearer to the switch member 20, the advance of the metal pot toward the mold, preparatory to a casting operation, will cause deflection of the carriage 9 in a direction away from the screw 8, thereby tripping or re-

leasing the carriage with respect to the

115 120 125 130

1 screw, with the result that the carriage 9 is returned or restored to its initial position by the spring 15. The alternate advance of the carriage 9 by the screw 8 and its tripping 5 and return by the advancing movement of the metal pot will take place at intervals which will be determined by the time elapsing between two successive casting operations, but if the casting operation is not re- 10 peated within the period of time for which the cut-out is set, the carriage 9 will continue its advance by the screw 8, without being tripped, and the projection 25 on the carriage will engage the switch member 20 15 and force its upper end 24 out of contact with the terminal 18 of the switch, thereby interrupting the motor and light circuit. This action, for example, would take place should the operator leave the machine without stopping it by manipulation of the usual 20 manual switch.

Obviously, the cut-out can be constructed or adjusted to interrupt the circuit, after any desired period of time has elapsed following 25 the performance of its periodic cycle. For example, the thread on the screw 8 may be constructed with different pitches to vary the time elapsing since the performance of its periodic cycle, before stopping the machine. It is generally preferable, however, to so construct or adjust the cut-out that it will permit the machine to continue its operation for a sufficient length of time after the operator may leave it, to enable the machine 30 to automatically dispose of the last line assembled and to distribute all of the matrices which may have been used in such operation, into the magazine. The machine may be instantly restarted when desired, by 35 rotating the handle or lever 26 to cause release of the carriage from the switch and screw.

Obviously, any suitable or well known devices may be used to minimize or prevent 45 sparking or burning of the switch contacts and it will also be understood that any suitable form of switch may be employed other than the one shown. Furthermore, while the cut-out is shown and described herein as 50 controlled by the metal pot, any other part of the machine which operates within the periodic cycle thereof may be utilized as a means for controlling the cut-out.

I claim as my invention:—

55 1. An automatic cut-out for typographical machines of the class employing electric current and embodying an operating part movable periodically during the normal operation thereof, comprising a switch for controlling the supply of electric current to the machine, a member which is advanced, during 60 the operation of the machine, from a starting position toward a position to cause the switch to cut off the supply of electric

current to the machine, and means controlled 65 by said periodically movable part to cause restoring of said member to its starting position.

2. An automatic cut-out for typographical machines of the electric motor driven class 70 embodying a periodically-movable operating part, comprising a switch for controlling the supply of electric current to the driving motor, and means controlled by said periodically-movable part of the machine and operative alternately in a direction to cause actuation of the switch to cut-off the supply of electric current to the driving motor and in a reverse direction to avoid such actuation 75 of the switch.

3. An automatic cut-out for typographical machines of the linotype class employing electric current and embodying an operating part movable intermittently during the usual operation of the machine, comprising 80 a switch for controlling the supply of electric current to the machine, and means advanced during the operation of the machine toward a position to cause the switch to cut off the supply of electric current to the machine and restored to its starting point prior to its reaching said position by the operation of said intermittently movable part of the machine. 85

4. An automatic cut-out for typographical machines of the class employing electric current and embodying an operating part movable intermittently during the operation of the machine, comprising a switch for controlling the supply of electric current to the machine, and a device having means for advancing it, during the operation of the machine, to cause the switch to cut off the supply of electric current to the machine and also means for restoring it controlled by the intermittently movable part of the machine. 90 100

5. An automatic cut-out for typographical machines of the linotype class, comprising an electric switch for controlling the supply of electric current to the machine, a device having means for advancing it, during the operation of the machine, to cause the switch to cut off the supply of electric current to the machine, and means controlled by the performance of a casting operation by the machine for rendering said device inactive 110 115 relatively to the switch.

6. An automatic cut-out for typographical machines of the class employing electric current and embodying casting mechanism 120 operative intermittently under control of the operator, comprising a switch for controlling the supply of electric current to the machine, and a device having means for advancing it, during the operation of the machine, to cause the switch to cut off the supply of electric current to the machine and having means controlled by the operation of 125

- the casting mechanism of the machine for preventing completion of the advance of said device.
7. An automatic cut-out for typographical machines of the class employing electric current and embodying continuously running operating parts and parts operating intermittently under control of the operator, comprising a switch for controlling the supply of electric current to the machine, and a device having means driven by one of the continuously running parts of the machine, and operative after the lapse of a predetermined period of time, to cause the switch to cut off the supply of electric current to the machine, and also having means controlled by one of the intermittently operating parts of the machine for preventing operation of said device.
- 10 8. An automatic cut-out for typographical machines of the class employing electric current and embodying a continuously running operating part and an intermittently moving operating part set into operation by the operator, comprising a switch for controlling the supply of electric current to the machine, a device operative to actuate the switch to cut off the supply of electric current to the machine, means operative by the continuously running part of the machine to advance the device to actuate the switch after the lapse of a predetermined period of time, and means controlled by the intermittently moving part of the machine to restore said device prior to its actuation of the switch.
- 15 9. An automatic cut-out for typographical machines of the class embodying an intermittently operative part, comprising a cut-out, a spring-tensioned travelling member operative against its spring tension, when advanced in a direction to actuate the cut-out, means driven from the machine and cooperative with said travelling member to advance it in said direction, and means controlled by said intermittently operating part for interrupting the advance of said travel-
- ling member at any point in its advance and for causing the travelling member to return to its starting position.
10. An automatic cut-out for typographical machines embodying an intermittently movable operating part, comprising a device which controls the operation of the machine, a member movable during the operation of the machine in a direction and toward a position to actuate said device to interrupt operation of the machine, said member having means for returning it to its starting position, and means controlled by said intermittently movable operating part to cause restoring thereof to its starting position.
- 15 11. An automatic cut-out comprising a switch, a revoluble screw, a carriage having a tooth to engage and follow the thread of the screw and a part to engage and actuate the switch, a rock shaft supporting the carriage to travel longitudinally of the screw and rotatable to disengage the tooth on the carriage from the thread on the screw, and means for actuating the rock shaft intermittently.
- 20 12. An automatic cut-out comprising a switch, a revoluble screw, a carriage guided to travel along the screw and having a tooth to engage and follow the thread of the screw and a part to engage and actuate the switch, a spring normally holding the tooth on the carriage in operative engagement with the thread on the screw, a spring normally acting to restore the carriage to initial position, means for revolving the screw continuously, and means operative intermittently to disengage the tooth on the carriage from the thread of the screw to cause restoration of the carriage.
- 25 30 35 40 45 In testimony whereof I have hereunto set my hand in presence of two subscribing witnesses.

EDWIN W. PIERSON.
